DESIGN FOR A STOCKING-FABRIC.

To all whom it may concern:

Be it known that I, THOMAS DOLAN, of the city and county of Philadelphia, State of Pennsylvania, have originated a new Design for a Stocking-Fabric; and I do hereby declare that the accompanying drawing, and following explanation thereof, form a full, clear, and exact description of the said design.

In the drawing, the figure represents sufficient of a stocking-fabric to illustrate the design, the most prominent features of which are the three parallel patterns A A A, and the intermediate zigzag stripes B B.

Each pattern, A, consists of a combination of zig-

zag stripes, arranged in the manner clearly illustrated in the drawing.

Irrespective of the colors employed,

I claim the design for a stocking-fabric, substantially as described and represented in and by the accompanying drawing.

In testimony whereof, I have signed my name to this specification, in the presence of two subscribing witnesses.
